VENETIAN BLIND VANE SPACER

Robert S. King, Oak Park, Ill.

Application December 10, 1951, Serial No. 260,865

7 Claims. (Cl. 160—172)

1

My invention relates to a Venetian blind of the vertical type and more particularly to a vane spacer for use therein. This type of blind has a headframe with a headframe floor and vertically disposed vanes. In this type of blind it is generally contemplated that each vane will be supported in a vertical position by an appropriate vane shaft extending through a longitudinal slot in the headframe floor.

Each vane spacer is adapted to receive a vane shaft so that the vane shaft and its depending vane may be rotated about their vertical axis. Further, the vane spacer, which is positioned above the longitudinal slot, is adapted to be moved horizontally along the headframe floor of the blind.

One object of my invention is to provide a vane spacer whereby the vanes of a Venetian blind may be equidistantly spaced across the blind proper and which may be moved in either direction across the face of the blind.

Another object of my invention is to provide a vane spacer whereby the vanes of a Venetian blind may be progressively spaced across the blind proper and whereby spacing movement is controlled by the vane spacer.

Another object is to provide a spacer that constitutes a unitary supporting means for each vane which cooperates to move the individual vane transversely of the window and which allows the vane to rotate on its vertical axis.

Another object of my invention is to provide a spacer of this character that is simple in construction, inexpensive to manufacture, easily installed and highly resistant to wear and to the stresses and strains which are placed upon vane spacers during normal operation.

Prior Venetian blinds have generally resorted to separate mechanisms to support the vane and to effect equal spacing thereof. The prior spacing means have generally been of a pliable material such as tapes and strings which are subject to wear and consequent periodic replacement. Also, they tend to bind in use.

In the present structure each vane is supported and spaced by my unitary vane spacer. My vane spacer, being constructed of rigid material such as metal, is not subject to wear under ordinary use, and therefore need not be replaced during the life of the blind.

Other objects and advantages of my invention as a spacing device will be apparent as the description proceeds, reference being had to the accompanying drawings which illustrate one structural form of the invention. It is to be understood, of course, that in commercial appli-

cations of the invention various details might well vary from those here shown and described.

In the drawings:

Fig. 1 is a perspective view, partly broken away, of the headframe floor of a venetian blind of the vertical vane type, showing the assembly of my vane spacers;

Fig. 2 is a perspective view of a single vane spacer.

Referring to the drawings, and particularly to Fig. 1 thereof, my vane spacers are illustrated in assembled relation on headframe floor 1 of a vertical type Venetian blind. Floor 1 has a longitudinal slot 2 through which pass vane shafts 16. Slot 2 allows the vane shafts and associated depending vanes to move laterally of the headframe.

A drive element 6, located at the movable end of the assembly, is adapted to be moved back and forth along slot 2 by suitable traversing means 14.

The illustrated embodiment of my vane spacer (Fig. 2) is formed from a single length of wire. One end of this wire is bent into a vertically disposed loop 21 which defines a first horizontal aperture 11. The wire then follows a rearward course from the top of loop 21 to a point where it has a horizontal U-bend 22 which defines a vertical opening 8 at the rear top of the vane spacer. The wire continues to the front of the vane spacer where it is provided with a vertical U-bend 23, the lower leg of which lies in the bottom plane of the vane spacer. U-bend 23 defines a second horizontal aperture 10.

The wire is then formed with a second horizontally disposed U-bend 24 which provides vertical opening 9 at the rear of the vane spacer below and in spaced relation from the first horizontal U-bend 22. This structure forms a vane spacer body having two spaced sidewalls, one comprising vertical loop 21 and the other comprising vertical U-bend 23. The sidewalls have aligned apertures 11 and 10, respectively, and aperture 11 is smaller than aperture 10, as shown in the drawing. The body also has a vertical opening 18 therethrough comprising the individual vertical opening 8 and 9 of horizontal U-bends 22 and 24, respectively.

Drive element 6 has the same body structure as has thus far been described for the vane spacer.

Following U-bend 24 the wire is bent in a generally vertical right angle bend 19 substantially midway between the front and the rear of the spacer body.

Next, the wire is bent in a laterally extending right angle bend 20. The laterally extending wire length is bent in an arcuate shape to form spac-

ing portion or spacing element 5, the free end of which is bent at a right angle to form a stop 12.

It is apparent that by means of right angle bends 19 and 20 there is formed an arcuate spacing element 5 which extends laterally from the vertical midpoint of the smaller apertured side of the vane spacer body in a direction generally perpendicular thereto. Thus, any longitudinal force exerted on said spacing element will generally be applied to the central portion of the body.

Referring to Fig. 1, it will be seen that the left hand vane spacer of the assembled series of vane spacers is engaged by an anchor 4 attached to a post 3 by means of an anchoring loop 13. Anchor 4 is comparable in size and shape to spacing element 5 of each vane spacer.

In use, each vane spacer is associated with one end of a vane 17. The vane end is provided with a shaft 16 (Fig. 1) that extends through the vertical opening 18 in the vane spacer. A collar 25 at the end of shaft 16 rests on the top of the vane spacer, as shown at the right in Fig. 1, and the vane spacer rests on the headframe floor 1 with shaft 16 extending through slot 2. Vane rotation element 7 is integral with collar 25 and controls the degree of rotation of vane shaft 16 and its associated vane. Vertical opening 18 is large enough to allow free rotation of the vane shaft 16.

Anchor 4, the vane spacers and the drive element 6 are assembled above slot 2 of headframe floor 1. Anchor 4 is coupled to the adjacent vane spacer by slidingly passing the free end thereof through horizontal apertures 10-11 of said vane spacer. Stop 12 of anchor 4 engages the peripheral edge of horizontal aperture 11 formed by loop 21 of one of the sidewalls of said vane spacers when the vane spacers are moved away from each other during traverse movement as the blind is moved to its open position. In a similar manner spacing element 5 of each vane spacer is slidingly coupled to the next adjacent vane spacer through the interaction of stop 12 and the peripheral edge of horizontal aperture 11 formed by loop 21 of the sidewalls of each of said vane spacers. The last vane spacer is similarly slidingly coupled to drive element 6, as shown.

In Fig. 1, the coupled vane spacers are illustrated in the positions they occupy when the traversing arrangement has been used to bring the blind to its nearly fully opened position. The traversing force has been applied to move drive element 6 to the left. As shown, this element has fully telescoped the spacing element 5 of the adjacent vane spacer, and the latter has been moved to the left so as to fully telescope the spacing element 5 of the next spacer. The same is true of the next three spacers.

Additional traversing force applied to drive element 6 will bring the two separated vane spacers together in the same manner, and finally will cause the last vane spacer to be moved to the end of slot 2. In this condition the blind is fully open.

As the spacing element 5 of each vane spacer telescopes the adjacent vane spacer, the spacing element 5 swings forward, looking at Fig. 1. This swinging motion is accommodated without binding because one of the horizontal apertures in each spacer is larger than the other. In the illustrated example, aperture 10 is larger than aperture 11.

When it is desired to close the blind, the traversing force is applied to move drive element 6 to the right. The element moves to the right and when it has been separated from the adjacent

vane spacer by the amount permitted by spacing element 5, the periphery of horizontal aperture 11 formed by loop 21 of drive element 6 is engaged by stop 12 of the adjacent vane spacer. Continued movement of element 6 thus results also in moving the adjacent vane spacer until it in turn is engaged by stop 12 of the next vane spacer as described. This process is progressively repeated until drive element 6 has been moved to its extreme right hand position in the headframe. At this time the blind is fully closed and the individual vanes are properly spaced in the blind, anchor 4 serving to space the last vane at the extreme left (Fig. 1) as described. The spacing of each vane, as previously mentioned, is measured by the length of the spacing element 5 of each vane spacer.

From the above description it is thought that the construction and advantages of my invention will be readily apparent to those skilled in the art. Various changes in detail may be made without departing from the spirit or losing the advantages of the invention.

Having thus described my invention, what I claim as new and desire to secure by Letters Patent is:

1. A Venetian blind structure comprising a headframe having a floor with a slot extending longitudinally thereof, a plurality of vertical vanes, each of which has a shaft extending through said slot, a plurality of vane spacers positioned above said slot, each vane spacer comprising a body having a vertical opening therethrough for receiving a vane shaft for rotation therein, said body having a pair of spaced sidewalls, each of said sidewalls having a horizontal aperture, one of said apertures being smaller than the other, an elongated arcuate spacing portion extending from the smaller apertured side of said body in a direction generally perpendicular thereto, said spacing portion having stop means at the free end thereof, said vane spacers being arranged in a series with the spacing portion of one spacer extending through the apertures of an adjacent spacer, an anchor at one end of the series and having one end thereof attached to said floor adjacent to one end of said slot and having a stop portion at its other end, said anchor extending through the apertures of the first vane spacer of the series, a drive element comprising a body similar in structure to the said vane spacer body and disposed at the other end of the series, the shaft of one of said vanes extending through the vertical opening of said drive element, traversing means drivably connected to the drive element, the spacing portion of the last vane spacer of the series extending through the apertures of said drive element, said stop means and said spacing portion being arranged to engage a sidewall of the adjacent body whereby to limit movement of the vane spacers and drive element in relation to said slot.

2. A Venetian blind structure comprising a headframe having a floor with a slot extending longitudinally thereof, a plurality of vertical vanes, each of which has a shaft extending through said slot, a plurality of vane spacers positioned above said slot, each vane spacer comprising a body having a vertical opening therethrough for receiving a vane shaft for rotation therein, said body having a pair of spaced sidewalls, each of said sidewalls having a horizontal aperture, one of said apertures being smaller

than the other, an elongated arcuate spacing portion extending from the smaller apertured side of said body in a direction generally perpendicular thereto, said spacing portion having stop means at the free end thereof, said vane spacers being arranged in a series with the spacing portion of one spacer extending through the apertures of an adjacent spacer, an anchor at one end of the series and having one end thereof attached to said floor adjacent to one end of said slot and having a stop portion at its other end, said anchor extending through the apertures of the first vane spacer of the series, a drive element comprising a body similar to structure to the said vane spacer body and disposed at the other end of the series, the shaft of one of said vanes extending through the vertical opening of said drive element, traversing means drivably connected to the drive element, the spacing portion of the last vane spacer of the series extending through the apertures of said drive element, said vanes, said spacers, said drive element and said traversing means being so arranged in relation to one another that movement of said traversing means in either direction will cause corresponding movement of the vanes progressively.

3. In a Venetian blind structure comprising a headframe having a floor with a slot extending longitudinally thereof, a plurality of vertical vanes each having a shaft extending through said slot, an anchor having one end attached to said floor adjacent one end of said slot and having stop means at its other end, a drive element above the other end of said slot, a plurality of vane spacers positioned above said slot between said anchor and said drive element, each vane spacer comprising a body having a vertical opening therethrough for receiving a vane shaft for rotation therein, said body having a pair of spaced sidewalls, a horizontal aperture in each of said sidewalls, one of said apertures being smaller than the other, an elongated arcuate spacing element extending from the smaller apertured side of said body in a direction generally perpendicular thereto, said spacing element having a stop means at the free end thereof, said drive element having a body similar in structure to the aforesaid vane spacer body, said vane spacers being arranged in series, the spacing element of each vane spacer except the last of the series extending loosely through the sidewall apertures of an adjacent vane spacer, the free end of said anchor extending loosely through the apertures of the first vane spacer of the series extending loosely through the apertures of the drive element.

4. A vane spacer formed of a single length of wire, said length of wire having a vertically disposed loop at one end, the wire continuing rearwardly from the top of said loop, a first horizontal U-bend at the rear of the spacer, a vertical U-bend at the front of the spacer and laterally spaced from said loop, a second horizontal U-bend at the rear of the spacer vertically spaced from said first horizontal U-bend, a generally right angle vertical bend substantially midway between the front and rear of the spacer, a laterally extending right angle bend substantially midway between the bottom and top of the spacer, the laterally extending bend being arcuate in shape and having its free end bent at a right angle to form a stop.

5. A vane spacer comprising a body having a vertical opening therethrough adapted to rotatably receive a vane shaft, said body having an elongated arcuate spacing element extending laterally therefrom, stop means at the free end of said element, said body also having a horizontal opening therethrough adapted to slidably receive the arcuate spacing element of an adjacent vane spacer, said stop means being effective to prevent disengagement of said spacing element and said adjacent vane spacer.

6. A vane spacer comprising a body having a vertical opening therethrough adapted to rotatably receive a vane shaft, said body having a pair of spaced sidewalls with a horizontal aperture in each, one of said apertures being smaller than the other, an elongated arcuate spacing element extending from the smaller apertured side of said body in a direction generally perpendicular thereto, and stop means at the free end of said element.

7. A vane spacer comprising a body having a vertical opening therethrough adapted to rotatably receive a vane shaft, said body having a pair of spaced sidewalls with a horizontal aperture in each, one of said apertures being smaller than the other, an elongated arcuate spacing element extending from the central portion of the smaller apertured side of said body and so arranged in relation to said body that any longitudinal force exerted on said spacing element will be applied to the central portion of said body, and stop means at the free end of said element.

ROBERT S. KING.
